TURBULENCE STRIP FOR RADIATOR TUBES

Walter R. Ramsaur, Racine, Wis., assignor to Young Radiator Company, Racine, Wis., a corporation of Wisconsin

Application January 7, 1938, Serial No. 183,740

3 Claims. (Cl. 138—38)

The present invention relates to means for causing the liquid passing through the tubes to violently impinge the walls of the tubes at closely spaced intervals, thus to increase the heat transfer capacity of the device.

Further objects of the present invention are to provide a turbulence strip which will fit snugly in the tube but may be easily inserted, removed and replaced.

One of the useful applications of the present invention is to remedy an inherent defect in oil cooling cores, wherein the oil tends to cling to the walls of the tubes and travel at a great speed at the center of the tubes thereby requiring major heat transfer through the slowly moving oil.

The present invention was devised to prevent the surface oil from clinging to the walls of the tubes and cause all of the oil in the tubes to turn over and over and wipe the wall of the tube in a manner which will insure an equal temperature of all of the oil as it passes through the tubes, thus to greatly increase the capacity of the device.

To these and other useful ends my invention consists of parts, combinations of parts or their equivalents and mode of operation as described and claimed and shown in the accompanying drawing in which:

Fig. 1 is a fractional transverse sectional view through a radiator having a single row of tubes which are provided with a multiplicity of spaced fins.

Fig. 2 is an enlarged transverse view of the turbulence strip shown in Figure 1, taken on line 2—2 of Figure 1.

Fig. 3 is an enlarged fractional side view of the strip as shown in Figures 1 and 2.

Fig. 4 is an enlarged fractional side view of the turbulence strip before being formed into the shape shown in Figure 1.

Fig. 5 is a side view of a modification.

Fig. 6 is an edge view of the modification illustrated in Figure 5.

As thus illustrated, reference numerals 9—9 designate the headers of the radiator. Numeral 10 designates the tubes which operatively connect the headers together.

I provide the usual closely spaced fin strips 11. Turbulence strips, which in their entirety are designated by reference character A are provided being preferably formed as illustrated in Figures 1, 2 and 3. These strips before being formed or zig-zagged are clearly illustrated in Figure 4 having alternately wide and narrow portions 13 and 14. A center portion of member 13 is removed as at 15 and portions 16—16 are cut free as at

17. After the strips have been thus formed they are zig-zagged as illustrated in Figure 1.

The bends are preferably made on a transverse line as at 18—18. When these bends are made, the freed members 16 are bent outwardly 5 in opposite directions alternately, as clearly indicated in Figures 1 and 2. It will be seen that the bends for members 16 are parallel to and preferably on the same plane as the bends in members 13. After the strips have been formed the 10 free ends of members 16 will be on nearly the same transverse plane as illustrated in Figure 3. Thus when viewing the strip from its end as in Figure 2 it will be seen that the free corners of members 16 will contact the walls of the tubes and that the corners of members 13 may also contact the walls of the tubes. Thus as the oil passes through the tubes it will impinge upon members 14 and the walls of the tubes and be diverted transversely into the walls of the tubes. The oil will also impinge upon member 16 on one 20 side and be caused to again violently impinge upon the walls of the tubes in the same manner.

On the other side of the turbulence strip the 25 moving oil will contact members 16 and be diverted into members 13 from whence it will be directed against the walls of the tubes.

Thus it will be seen that there is in fact no direct path for the oil except the small V-shaped path as at 21, however, the oil at these points will be diverted and caused to violently impinge upon the walls of the tubes by the oil streams as they pass around member 16 or from the surface of members 13 and 14. Clearly the oil will be broken up into many diverging paths and caused to impinge upon the walls of the tubes many times as it passes through the tubes.

In the preferred design shown, I provide pipe plugs 25 for openings which are made large enough for the insertion of an expander with 40 which to expand the tubes into the header plate and through which the strips are inserted. Clearly after the assembly has been completed and the radiator placed into service the strips may be easily removed and replaced.

One of the advantages of my turbulence strips is that they may be pulled by means of a wire into the tubes, at which time the strip will be slightly elongated and thus made to pass freely 50 into the tube and then assume a normal size which is made large enough to fit snugly in the tube. The strips may be made long enough so plugs 25 will slightly compress the strips, thus to more firmly hold them in contact with the walls of the tubes.

In Figures 5 and 6, I illustrate a modification. These strips before being formed are very similar to the strips shown in Figure 4 except that members 16 will be removed, leaving an opening 5 26 in the center of the wide portion 21. The narrow portion 28 of the strip being preferably about the same length as members 27. This strip after being blanked is bent in the shape illustrated in Figure 6 at points 29. Thus when viewed from 10 the end the appearance of the strip will be very similar to the strip as illustrated in Figure 2 less members 16 and the operation being somewhat similar to the other strip except that the oil would be caused to impinge upon the walls of the tubes on one side by members 28 and on the 15 other side by members 27.

It will be understood that various modifications may be made without departing from the spirit and scope of my invention; for example, the bends with which to form the strips as in 20 Figure 1 may be made at a point midway lines 18-18 or otherwise.

Having thus shown and described my invention I claim:

25 1. A device of the class described, comprising a radiator tube having therein a turbulence strip, said strip comprising alternately spaced wide and narrow rectangular in shape portions, the wide portions each having centrally positioned

relatively large rectangular in shape openings, said strips having a zig-zag shape, the bends being positioned transversely to the strip and adjacent the ends of said narrow strips.

2. A device of the class described, comprising a tube having therein a turbulence strip, said strip comprising alternately spaced wide and narrow portions, the wide portions each having centrally positioned openings which are formed by cutting portions free which are bent outwardly 10 in opposite direction on a transverse line and adjacent the ends of said narrow strips, said strips having a zig-zag shape, the bends being positioned transversely and adjacent the ends of said narrow and wide strips. 15

3. A device of the class described, comprising a radiator tube having therein a turbulence strip, said strip comprising alternately spaced wide and narrow rectangular in shape portions, the wide portions each having centrally positioned rectangular in shape openings which are formed by cutting portions free which are bent outwardly 20 in opposite directions on a transverse line with and adjacent the ends of said wide strips, said strips having a zig-zag shape, the bends being 25 positioned transversely and adjacent the ends of said openings.

WALTER R. RAMSAUR.
